[57] CLAIM

The ornamental design for a bottle crate, as shown and described.

DESCRIPTION

FIG. 1 is a side elevational view of a bottle crate showing my new design, the remaining three sides being the same in appearance.

FIG. 2 is a fragmentary sectional view taken on the line 2—2 of FIG. 1 showing only the right half of the bottle crate.

FIG. 3 is a top plan view thereof.

FIG. 2.

FIG. 1.

*FIG. 3.**FIG. 4.*
